UNITED STATES PATENT OFFICE.

ADOLPH MAEULEN, OF WILLIAMSPORT, PENNSYLVANIA, ASSIGNOR TO WILLIAMSPORT MIRROR & GLASS COMPANY, OF WILLIAMSPORT, PENNSYLVANIA.

WINDOW-VENTILATOR.

1,100,678.

Specification of Letters Patent. Patented June 16, 1914.

Application filed January 15, 1914. Serial No. 812,249.

To all whom it may concern:

Be it known that I, ADOLPH MAEULEN, a citizen of the United States, residing at Williamsport, in the county of Lycoming and 5 State of Pennsylvania, have invented new and useful Improvements in Window-Ventilators, of which the following is a specification.

The invention particularly relates to window ventilators employing a transparent front plate and collapsible segmental side members of extremely light and strong construction.

In connection with the accompanying 15 drawing, forming a part of this specification and wherein like numerals of reference designate corresponding parts throughout the several views: Figure 1 is a view in side elevation of the side or end members of the 20 ventilator with the front plate and window structure in vertical section. Fig. 2 is a vertical sectional view through the side or end member. Fig. 3 is a transverse sectional view taken through Fig. 2 on the line 3—3. 25 Fig. 4 is a view in side elevation of a portion of a modified form of side or end member with the front plate in vertical section. Fig. 5 is a side elevation of a rear portion of Fig. 4. Fig. 6 is a top plan view of a modified form of side or end member. Fig. 7 is 30 a view in elevation of a portion of the form of Fig. 6, and Fig. 8 is a vertical sectional view taken through Fig. 1 on the line 8—8.

Reference numeral 1 designates the window frame, 2 the window sill, and 3, the window sash, to which the invention is applied. The invention consists broadly of a front glass plate 4 and two sides or end members. In the drawing only one side or 35 end member is illustrated, but it will be understood that there is a side or end member attached to each end of the front plate 4 and to each side of the window frame. Each side or end member consists of two segmental plate sections 5 and 6. The side plate 5 is bent inwardly at right angles entirely along its front edge forming a flange 7 behind which the glass front plate 4 is placed. The front plate 4 is engaged along its 40 opposite or rear side by a flange 8 of a separate L-shaped bar, the other flange 9 of said bar bearing flat upon the side plate 5. The flange 8 is adjustable toward the flange 7 by means of bolts 10 to securely clamp the front plate 4. The upper edge of the plate 5 is

cut out as at 12 thereby providing spaced lugs or stops 14—15, one adjacent each side edge of the plate 5. The side plate 6 comprises front and rear spaced walls 16 and 17, integrally connected along their side edges 60 as at 18, by bending one from the other. The upper end portion 19 of the wall 17 is bent over upon the wall 16 closing the upper end of the plate 6 against entry of rain water. A portion 20 of the wall 17, which 65 extends as at 21 beyond the side edge of the wall 16 throughout, is bent around the side edge of the wall 16 embracing between itself and said wall 16 the bent over portion 19 of the wall 17, the former openings 22 permitting 70 insertion of a screw driver to drive screws 22' into the apertures 22' to secure the plate 6 to the side 1 of the window frame. The plate 5 is inserted between the walls 16 and 17 of the plate 6, the stop 20 75 being received in the cut-out portion 12 and engageable with stops 14 and 15. Both plates 5 and 6 at their lower ends have registering openings to receive pivot screw 25 which passes into the window sash. When 80 secured together in this manner, the plate 5 is freely movable between the walls 16 and 17 of plate 6, the stop 15 engaging stop 20 preventing entire withdrawal of plate 5 from the other 6. The plates can only be 85 separated entirely by removal of the pivot screw 25.

In the modified forms, the plates 5 and 6 are the same as in Fig. 1, except with respect to the receiving portion for the front 90 plate 4. In Figs. 4 and 5 the L-bar 26 is similar to the bar 8—9 of Fig. 1 though turned around. This bar has beaded fastenings 27 which enter openings 28 and slide into diagonal slots 29 in the plate 5 to crowd the bar against the glass front plate 4. In Figs. 6 and 7, the side portion of plate 5 is 95 bent to provide inwardly extending double wall flange 30 and single flange 31, connected by portion 32 aligned with the body portion of the plate 5. Between these parallel flanges 30 and 31, the glass front plate is inserted.

What is claimed as new is:—

1. In a window ventilator, a segmental 105 side plate having means for connection with a front member, a second segmental side plate having double walls and slidably receiving between its walls the first plate, a stop extending across the space between the 110

walls of the second plate, the first plate having a cut out portion receiving said stop and the end walls of the cut-out portion being engageable with the stop to arrest movements of the first plate in the second plate, and said plates being pivoted together.

2. In a window ventilator, a segmental side plate having means for connection with a front member, a second segmental side plate bent upon itself and slidably receiving between its walls the first plate, one wall of the second plate extending beyond the other wall and the same wall having a portion bent around the said other wall forming a stop, the first plate having a cut-out portion receiving said stop.

3. In a window ventilator, a segmental side plate having means for connection with a front member and also having a cut-out portion, a second segmental side plate bent upon itself forming double walls, the upper edge of one wall being bent upon the other wall, a portion of the side edge of one wall being bent upon the other wall forming a stop, said plates being pivoted together with the stop received within the said cut-out portion.

4. In a window ventilator, a segmental side plate having means for connection with a front member, stops extending beyond said

upper edge, a second segmental side plate of double wall formation, the walls being connected along their side edges, the upper edge of one wall being bent around the other wall, a portion of the side edge of one wall being bent around the other wall and constituting a stop, the side edge of one of said walls extending beyond the other and beyond the last-mentioned stop, the first side plate being slidably received between the walls of the second side plate, the stop of the second side plate being received between the stops of the first side plate, and the said plates being pivoted together adjacent their lower ends.

5. In a window ventilator, a side plate having a right angular flange along one edge, an L-shaped member having one of its flanges parallel with and movable with relation to said right angular flange, and the other flange of the L-shaped member bearing flat upon the said side plate.

In testimony whereof I have hereunto set my hand in presence of two subscribing witnesses.

ADOLPH MAEULEN.
